FORM AND CARBON CARRYING
CONTROL DEVICE

George Henry Sargent, Toronto, Ontario, Canada, assignor to The Egry Register Company, Dayton, Ohio, a corporation of Ohio

Application November 28, 1933, Serial No. 700,112

9 Claims. (Cl. 197—126)

This invention relates to attachments for use in connection with typewriters, and has for its object to provide an attachment that will serve to guide a plurality of superimposed strips of paper, with means thereon for supporting carbon sheets interleaved between the strips of paper.

It is particularly the object to provide an attachment in the nature of a frame, which has means for engaging a typewriter at one end, 10 guide means at its other end with intermediate means for temporarily supporting one or more sheets of carbon paper, and so supporting the sheets of carbon paper that they may be easily removed therefrom for use in connection with 15 strips of paper for writing purposes.

This invention also relates to a method of feeding sheets of carbon paper, interleaved between strips of paper, and supporting the sheets of carbon paper so that the strips of paper may be fed 20 independently thereof.

These and other advantages will appear from the following description taken in connection with the drawings.

Referring to the drawings:

Figure 1 is a side elevation of the attachment attached to a part of the typewriter, with the strips of paper and interleaved carbon sheets thereon, with the carbon sheets supported so that the strips of paper will travel independently 30 of the carbon sheets.

Figure 2 is a view similar to Figure 1 but with the upper part of the frame of the attachment broken away to show a connecting rod and the guides for the strips of paper, and showing also the carbon sheets unsupported and moving with the strips of paper.

Figure 3 is a front elevation.

Figure 4 is a section through the interleaved strips of paper, carbon sheets and the pasteboard strips for supporting the carbon sheets.

This attachment consists essentially of a frame composed of two side members 1, connected at their lower ends by a lower cross member 2, and 45 adjacent their upper ends by an upper cross member 3 (Figure 3). The ends of the lower cross member extend laterally from the frame to provide extensions 4, which have extending downwardly therefrom legs 5. Each leg has on 50 its lower end a hook 6 to engage a rod 7 of the typewriter 8. This typewriter has the usual platen 9.

The central parts of the cross members 2 and 3 are connected by means of a central bar 10. 55 Each side member adjacent the upper cross

member is bent to form a shoulder or ledge 11, as clearly shown in Figures 1 and 2. These shoulders serve to support the carbon sheets when it is desired to advance the strips of paper independently of the carbon sheets. The upper end 5 of each side member, beyond the upper cross member, is bent to form an arch or arcuate member 12. These arcuate parts of the side members are connected by means of a rod 12a, which not only serves to connect the upper ends of the side 10 members but acts as a support for the strips of paper passing over them and between two guides 13, located on the ends of the rod.

The superimposed strips of paper 14 have cross 15 perforations 15, by which the strips are marked off into sheets of paper (Figure 3). These sheets of paper overlie or are superimposed one upon the other. These sheets of paper are also provided, adjacent one end, with holes 16 for any suitable purpose. The sheets of carbon paper, interleaved and suspended between the strips of paper, are indicated by the numeral 17. Each sheet has on its upper end a narrow, thin pasteboard strip 18 (Figure 4) which extends laterally 20 from each side of the carbon sheet for supporting the carbon sheet, when desired, on the shoulder 25 11.

When a group of carbon sheets is used for the purpose of interleaving them between a plurality 30 of strips of paper, the ends of the pasteboard strips are held together by means of a cap or wrapper 19. By means of these caps or wrappers the pasteboard strips are held in proper relation to one another. While these strips are 35 described as made of pasteboard and pasteboard makes very serviceable strips, other materials may be used for this purpose.

In Figure 2 the typewriter is in operation and the superimposed strips and interleaved carbon 40 sheets are being advanced together. The carbon sheets do not extend to the end of the assembly of strips so there is a part of the end of the assembly of strips that may be engaged by the typewriter for feeding without feeding the carbon sheets.

After the writing has been finished the platen is caused to rotate so that the strips of paper and sheets of carbon move backwardly. After these have been moved back sufficiently so that 50 the strips 18 may be positioned on the shoulder 11, the paper strips are advanced sufficiently that the written parts may be torn off along the perforations. The supporting strips for the carbon sheets are then removed from the shoulder so 55

they may be advanced with the advancement of the strips of paper. The writing action is again repeated with an additional section of paper sheets in use, the paper sheets formerly written upon having been torn off.

5 I desire to comprehend within my invention such modifications as may be embraced within my claims and the scope of my invention.

Having thus fully described my invention,

10 what I claim as new and desire to secure by Letters Patent, is:

1. A typewriter attachment for supporting a sheet of carbon paper interleaved between strips of paper, said sheet of carbon paper having at 15 one end lateral projections, said attachment consisting of a frame having side members bent adjacent one end of the frame to form shoulders for receiving the projections.

2. In a typewriter attachment for supporting 20 a sheet of carbon paper interleaved between strips of paper, said sheet of carbon paper having at one end lateral projections, a frame having side members bent adjacent one end of the frame to form shoulders to receive the projections, and legs on the other end of the frame to 25 engage the typewriter.

3. In a typewriter attachment for supporting 30 a sheet of carbon paper between strips of paper, said sheet of carbon paper having at one end lateral projections, a frame having side members bent adjacent one end of the frame to form shoulders to receive the projections, legs on the other end of the frame to engage the typewriter, and guides on the frame adjacent the shoulders 35 for the strips of paper.

4. In a typewriter attachment for guiding a plurality of superimposed strips of paper and supporting sheets of carbon paper interleaved between the strips of paper, each carbon sheet 40 having at one end lateral projections, a frame having side members, one end of each side member being arcuate and connected to the other arcuate end by a rod, a shoulder on each side member adjacent the arcuate end, said shoulders 45 being adapted to receive said projections for supporting the sheets of carbon paper, and means on the other ends of the side members for attaching the frame to a typewriter.

5. In a typewriter attachment for guiding a 50 plurality of superimposed strips of paper and supporting sheets of carbon paper interleaved between the strips of paper, each carbon sheet having at one end lateral projections, a frame having side members, one end of each side member being arcuate and connected to the other arcuate end by a rod, means on the rod for guiding the strips of paper, a shoulder on each side member adjacent the arcuate end, said shoulders being adapted to receive said projections for 55 supporting the sheets of carbon paper, and means on the other ends of the side members for attaching the frame to a typewriter.

6. In a typewriter attachment for guiding a plurality of superimposed strips of paper and supporting sheets of carbon paper interleaved between the strips of paper, each carbon sheet having at one end lateral projections, a frame 5 having side members, one end of each side member being arcuate and connected to the other arcuate end by a rod, guards projecting up from the rod to guide the strips of paper, a shoulder on each side member adjacent the arcuate end, 10 said shoulders being adapted to receive said projections for supporting the sheets of carbon paper, and means on the other ends of the side members for attaching the frame to a typewriter.

7. A typewriter attachment for guiding a 15 plurality of superimposed strips of paper and supporting sheets of carbon paper interleaved between the strips of paper, said attachment comprising a frame consisting of a lower cross member having at each end a leg, side members, 20 each side member being attached at one end to said cross member adjacent a leg and having its other end arcuate and bent adjacent the arcuate part to form a shoulder, a rod connecting the arcuate ends, and an upper cross member connecting the side members adjacent the shoulders.

8. A typewriter attachment for guiding a plurality of superimposed strips of paper and supporting sheets of carbon paper interleaved 30 between the strips of paper, said attachment comprising a frame consisting of a lower cross member having at each end a leg, side members, each side member being attached at one end to said cross member adjacent a leg and having its other end arcuate and bent adjacent the 35 arcuate part to form a shoulder, a rod connecting the arcuate ends, guides for the strips of paper on the rod, and an upper cross member connecting the side members adjacent the shoulders.

9. An attachment for a typewriter having a 40 platen and pressure feed roll, comprising a frame disposed on the feeding side of the typewriter, spaced stationary projections fixed to the outer marginal portions of the frame outside the path of the work sheets and at a distance from the operative zone of the platen and pressure feed roll at least equal to the length of a carbon sheet, a carbon sheet holder movable relative to said frame on the feeding side of the typewriter, said carbon sheet holder having laterally-extending portions adapted to be engaged with said spaced projections, whereby when the said portions are engaged with said projections the carbon sheet holder is held immovably, irrespective of the movement of the work sheets during a feeding operation with the carbon sheet entirely removed from the operative zone of the platen and pressure feed rolls of the machine.
